UNITED STATES PATENT OFFICE

2,473,095

TILTING SALT BATH FURNACE

George Henry Stanley Grene, Watford, England,
assignor of one-half to Wild-Barfield Electric
Furnaces Limited, Watford, Hertfordshire,
England

Application October 26, 1945, Serial No. 624,691
In Great Britain November 1, 1944

6 Claims. (Cl. 13—23)

1

It is ordinary practice to tilt melting furnaces where there is a molten charge which can be poured. Salt bath furnaces are, however, used for the treatment of solid work pieces and it does not appear to have hitherto occurred to anyone to arrange for removal of the work by usual methods and to tilt the furnace when the salt is to be removed for cleaning out the bath or to provide readily for substitution of another salt for a different process.

The present invention provides a tiltable salt bath furnace, enabling this procedure to be readily carried out, and so to facilitate what is otherwise a laborious job of bailing out the molten salt to enable the accumulation of sludge at the bottom to be removed.

In the preferred forms the tiltable bath is readily removable; in cases where the amount of work to be carried out justifies it, separate baths can thus be used for the several salts and the baths can be changed so that contamination due to residual salt in the brickwork does not take place. The bath with its electrodes can be immediately lifted from the bearings and another dropped in place.

The above and other parts of the invention are embodied in a typical form illustrated by the accompanying drawings in which—

Fig. 1 is a front elevation,
Fig. 2 is a side elevation,
Fig. 3 is a plan.

Fig. 4 is a fragmentary sectional elevation, showing the bath structure and associated parts in working position, and

Fig. 5 is a similar view showing the workpiece removed, and the parts in position for pouring and collecting the salt.

The furnace comprises a body portion 1 which houses the conventional electrical gear, enclosing a contactor and isolator indicated at 2, step-down transformer at 3, controllable bi-metallic strip energy regulator at 4, ammeter 5 and indicator lamps 6, tapping switch 7 for the transformer with hand wheel 7a and knife switch elements 8. The main isolator switch handle 9 is at the back and a push-button type emergency stop switch 10 in front. The body portion 1 has a pair of forwardly projecting side wings or brackets 11, with elements 12 of the rotary supports for the bath arranged to receive the complementary elements or trunnions 13 on the bath 14. A removable mould 15 to receive the salt is connected with the bath by a channel 14', so that when the bath is tilted the salt can be carried on the front of the bath and may have a serrated or other ap-

2

propriate surface 15a on which the salt will lie as it solidifies, so facilitating breaking it up for use again. The electrical leads between the body portion and the bath are readily detachable for removal of the bath and as shown include knife blades 16 adapted to engage the fixed elements 8 which are connected to the electrodes 17 so that the electrical connection is automatically broken when the bath is tilted or removed. A cover 18 carried by the back of the bath encloses the electrical connections when the bath is in its normal upright position.

The use of the bath and the delivery of the salt from the bath to the removable mold 15 is best shown in Figs. 4 and 5. In Fig. 4 the bath is shown in its normal working position with a work piece 28' suspended from the branch 23 of the tool post 22 for treatment in the molten salt 29. On the other hand Fig. 5 shows the bath tilted as by tilting the tool post 22 which may also be employed as a tilting lever. When the bath is tilted, the molten salt is conveyed by the channel passage 14' to the mold 15 to be cooled and solidified, after which it may be readily removed for recovery of the salt. It is to be noted that the electric circuit to the electrodes is broken at the beginning of the tilting movement by the swinging of the switch blades 16 from the switch elements 8.

30 The bath is covered by a hood 19 with lugs 20 which centre it on the bath. The hood is provided with an observation window 21 that is preferably covered by a wire mesh or perforated metal sheet or the window may be formed by juxtaposed perforations in the sheeting forming the hood. In addition, the hood is provided with a relatively small central aperture 21' for the admission of the work piece 28'. The opening 21' is relatively small and centrally located and 35 the window 21 is covered by a mesh or the like to protect the operator from splashes.

40 The work is placed or suspended in the bath and removed after treatment in any normal or convenient way. As shown, a tool post 22 with a work suspension branch 23 is removably supported in a socket 24. The tool post or a separate lever can be inserted in the socket 25 on the side of the bath to tilt the bath when required. A portable pyrometer 26 is shown, carried when not in use in a further socket 27 in one of the wings.

45 In many cases it is convenient to provide a series of adjacent salt baths for successive stages of a process; for example one or more preheating baths, a hardening bath, a quenching bath, and possibly a further bath for secondary hardening.

The wings or brackets of the improved furnaces can readily be arranged to be bolted or otherwise attached against those of adjacent furnaces, so as to constitute a fixed battery of successive baths along which the work under treatment can be progressed. Bolt holes 28 are shown for this purpose.

I claim:

1. An electrode salt bath furnace to treat solid work pieces including a bath having an open top, means for carrying solid work pieces in the bath by suspension from above the open top of the bath, means for tilting the bath, electrodes for heating the bath mounted in the bath, electrode contact making and breaking means for making contact when the bath is in normal position and breaking contact when the bath is tilted, and means separably attached to the bath for receiving the whole of the salt from the bath when the bath is tilted.
2. An electrode salt bath furnace to treat solid work pieces including a bath having an open top, means for carrying solid work pieces in the bath by suspension from above the open top of the bath, means for tilting the bath, means separably attached to the bath for receiving the whole of the salt when the bath is tilted, electrodes for heating the bath mounted in the bath, means for removably supporting the bath with its electrodes on the furnace, and electrode contact making and breaking means for making contact when the bath is in normal position and breaking contact when the bath is tilted or removed.
3. An electrode salt bath furnace to treat solid work pieces, means for carrying the bath tiltably and removably, means for introducing and removing work pieces into and from the bath, electrodes for heating the bath, means for tilting the bath to deliver the salt from its effective position in the bath, removable means carried by the bath for receiving the salt delivered from the tilted bath, and electrode contact making and breaking means for making contact when the bath is in normal position and automatically breaking contact when the bath is tilted or removed.
4. A construction as defined in claim 3 wherein

5

the means for receiving the salt upon the tilting of the bath is formed with a serrated surface for forming a complementary surface to the salt solidifying thereagainst.

5. A salt bath furnace for treating solid work pieces and having spaced electrodes, means for supplying said electrodes with electric current, means for tilting the bath with the electrodes, a removable mould carried by the bath, and passage means connecting the mold with the bath for passing to the mold the whole of the salt from the bath as the bath is tilted.

6. A salt bath furnace for treating solid work pieces and having spaced electrodes, means for supplying said electrodes with electric current, removable cover means attached to and overlying the bath, an observation window in said cover, a work admitting opening in said cover, means for tilting the bath, a removable mould carried by the bath and receiving the whole of the salt from the bath as the bath is tilted, and contact elements located under the cover means and controlling the current through the electrodes.

GEORGE HENRY STANLEY GRENE.
